[57] CLAIM

The ornamental design for an athletic shoe upper, as shown and described.

DESCRIPTION

FIG. 1 is a perspective view of an athletic shoe upper, showing our new design;

FIG. 2 is a left side elevational view;

FIG. 3 is a right side elevational view;

FIG. 4 is a front elevational view;

FIG. 5 is a rear elevational view; and,

FIG. 6 is a top plan view.

The broken line showing of a shoe sole in FIGS. 1-6 is for illustrative purposes only and forms no part of the claimed design.
